UNITED STATES PATENT OFFICE.

CHARLES H. WILLSON, OF MEDFORD, ASSIGNOR TO JAMES W. BROOKS, OF PETERSHAM, AND FRANK F. STANLEY, OF SWAMPSCOTT, MASSACHUSETTS, TRUSTEES.

DESIGN FOR A NAIL OR SLUG.

SPECIFICATION forming part of Design No. 25,085, dated January 21, 1896.

Application filed December 18, 1895. Serial No. 572,608. Term of patent 3½ years.

To all whom it may concern:

Be it known that I, CHARLES H. WILLSON, of Medford, county of Middlesex, and State of Massachusetts, have invented and produced a certain new and useful Design for a Nail or Slug, of which the following is a specification, reference being had to the accompanying drawings, forming a part thereof.

Figure 1 of the drawings is an isometric view of a nail or slug, illustrating my design; and Fig. 2 is an end view thereof.

The leading feature of my design consists in a nail or slug having a rounded or cylindrical longitudinal edge, an adjacent portion lozenge-shaped in cross-section and intersecting the cylinder, and a larger triangular prism the base of which forms the other longitudinal edge of the nail or slug.

In the drawings the nail or slug is shown as comprising a lozenge-shaped portion *a* intersecting a cylinder *b* which forms one of the longitudinal edges of the nail or slug, the other longitudinal edge thereof being formed by the base *c'* of a triangular prism *c*, larger than the lozenge or cylinder, and intersecting the lozenge-shaped portion *a*.

I claim—

The design for a nail or slug, substantially as set forth.

In testimony whereof I have signed my name to this specification in the presence of two subscribing witnesses.

CHARLES H. WILLSON.

Witnesses:

JOHN C. EDWARDS,
FREDERICK L. EMERY.
